(57) **CLAIM**

The ornamental design for a support for a tabletop, as shown and described.

DESCRIPTION

FIG. 1 is a perspective view of a first embodiment of a support for a tabletop illustrating my new design;

FIG. 2 is front elevation of FIG. 1;

FIG. 3 is a rear elevation view of FIG. 1;

FIG. 4 is a right elevation view of FIG. 1;

FIG. 5 is a left elevation view of FIG. 1;

FIG. 6 is a top plan view of FIG. 1; and

FIG. 7 is a bottom plan view of FIG. 1;

FIG. 8 is a perspective view of a second embodiment of a support for a tabletop illustrating my new design;

FIG. 9 is front elevation of FIG. 8;

FIG. 10 is a rear elevation view of FIG. 8;

FIG. 11 is a right elevation view of FIG. 8;

FIG. 12 is a left elevation view of FIG. 8;

FIG. 13 is a top plan view of FIG. 8; and,

FIG. 14 is a bottom plan view of FIG. 8.

The broken lines in the figures depict environmental structure and portions of the support for a tabletop that form no part of the claimed design. The oblique shading lines indicate a reflective surface. The stippled regions indicate a matte surface. The vertical shading lines are to indicate contours and not surface ornamentation or texture.
